UNITED STATES PATENT OFFICE.

JOSEPH J. RUSSELL, OF TOLEDO, OHIO.

RADIATOR.

1,310,251.

Specification of Letters Patent.

Patented July 15, 1919.

Application filed June 26, 1917. Serial No. 177,095.

To all whom it may concern:

Be it known that I, JOSEPH J. RUSSELL, a citizen of the United States, residing at Toledo, in the county of Lucas and State of Ohio, have invented new and useful Improvements in Radiators, of which the following is a specification.

This invention relates to radiators such as are now commonly used in motor vehicles 10 for cooling the water of circulation which pass through the jacket of the engine.

The object of the present invention is to produce a radiator in which the core as a 15 whole is made up of several sections each of which is so constructed and mounted that it may be removed from the casing or housing of the radiator without removing or interfering with any of the other sections, enabling a leak or repair of any kind to be 20 made at any point in the removed section.

A further object of the invention is to construct each of the sections of the core in such manner that the water tubes are capable of expanding in case of the water freezing, without serious injury thereto.

With the above and other objects in view, the invention consists in the novel construction, combination and arrangement of parts, herein described, illustrated and claimed.

30 In the accompanying drawings:—

Figure 1 is a vertical longitudinal section through a radiator illustrating the improved construction.

Fig. 2 is an enlarged vertical transverse 35 section on the line 2—2 of Fig. 1.

Fig. 3 is a fragmentary section on the line 3—3 of Fig. 2.

Fig. 4 is a detail view illustrating the end connections between the horizontal runs of 40 the water tubes.

Referring to the drawings 1 designates a radiator casing which may be of any desired contour, the same being provided with the usual filling neck 2 and cap 3.

45 In carrying out the present invention, in the preferred embodiment thereof, the casing 1 has mounted therein a comparatively small top water compartment 4 and also a comparatively small bottom water compartment 5, the top compartment comprising an arcuate bottom wall 6 and the bottom compartment comprising a top arcuate wall 7. 8 designates the water inlet opening and 9 the water outlet opening.

55 The radiator is shown as comprising three core sections α as shown in Fig. 1 but it

will be apparent that the number of sections may be increased or diminished at will and in accordance with the desired water capacity of the radiator. Each of the sections comprises a plurality of horizontal runs b which are connected at numerous points by vertically extending strips c of metal which form connecting webs or braces between the horizontal runs b of each section α of the radiator core.

Referring now to Figs. 2 and 3, each of the horizontal runs b is composed of a top plate 10 and a bottom plate 11. The front portions 12 and the rear portions 13 of said plates lie in contact with each other and are soldered as indicated at 14 to form water tight joints to prevent leakage. The intermediate portions of the plates 10 and 11 are of stepped formation as clearly shown in Fig. 2 and are arranged in spaced relation to each other to leave a central horizontal waterway or passage 15, a downwardly tapering or contracting waterway 16 and an upwardly tapering or contracting waterway 17. All of the runs b are of corresponding formation as shown in Fig. 2 thereby leaving zigzag or sinuous air passages d between the superimposed horizontal runs b . The portions 12 and 13 of the top and bottom plates 10 and 11 are only connected at their extreme outer edges thus providing for expansion in case the water should freeze in the water tubes. This prevents serious injury to the water tubes. At their opposite ends, the runs b are connected by end chambers or vertical runs e each comprising an inner wall 18 and an outer wall 19. The connections e are arranged in the manner illustrated in Fig. 1 so as to provide for the continuous movement of the circulating water from top to bottom of each core section.

Each of the core sections α is provided at its upper end with an inlet connection 20 controlled by a stop cock 21 and connected by a liquid tight union 22 to the wall 6 of the top water compartment 4. In like manner the lower end of each core section is connected by a conduit 23 controlled by a stop cock 24 to the wall 7 of the bottom compartment 5 by means of a liquid tight union 25. The construction just referred to enables the water to be cut off both at the top and bottom end of each core section and also enables each core section to be disconnected at the top and bottom thereof from the top and bottom water compartments in order that

any desired section may be removed from the casing or housing of the radiator.

The construction hereinabove described greatly facilitates the assemblage of the essential parts of a radiator and enables repairs to be readily made by removing any section which needs repair. After a core section is removed from the casing 1, the vertical strips *c* may be cut or severed between any pair of runs *b* thus enabling the said runs to be sprung apart sufficiently to facilitate the resoldering or repair of the water tubes.

I claim:—

1. In a radiator, a core comprising a vertical series of terminally connected substantially horizontal runs, each run embodying a top plate and a bottom plate having their front and rear portions arranged in contact with each other and united by a water tight joint, the intermediate portions of said top and bottom plates being of stepped formation and arranged in spaced relation to each other to provide a central substantially horizontal waterway and inclined waterways at the front and rear of said horizontal waterway.

2. In a radiator, a core comprising a vertical series of terminally connected substantially horizontal runs, each run embodying a top plate and a bottom plate having their

front and rear portions arranged in contact with each other and united by a water tight joint, the intermediate portions of said top and bottom plates being of stepped formation and arranged in spaced relation to each other to provide a central substantially horizontal waterway and inclined waterways at the front and rear of said horizontal waterway, said inclined waterways being of tapering or contracting formation toward the front and rear connected portions of said top and bottom plates.

3. In a radiator, a core comprising a vertical series of terminally connected substantially horizontal runs, each run embodying a top plate and a bottom plate having their front and rear portions arranged in contact with each other and united by a water tight joint and their central portions arranged in horizontal parallelism and spaced apart to provide a central rectangular portion and upwardly and downwardly extending front and rear downwardly tapered portions, extending from and communicating with the central rectangular portion to provide extensible waterways and air passages having restricted central portions formed by the central rectangular portion of the waterways.

In testimony whereof I affix my signature.

JOSEPH J. RUSSELL.
